PORTABLE MECHANICAL LUNG

William H. Haverland, Morrison, Colo., assignor to J. J. Monaghan Company, Inc., Denver, Colo., a corporation of Colorado

Application May 2, 1955, Serial No. 505,319

14 Claims. (Cl. 128—30)

This invention relates to improvements in medical equipment of the type employed for inducing respiration in persons suffering from injury or disease which impairs the functioning of the natural respiratory apparatus and is directed particularly to a new and novel equipment of this type designed for use by persons suffering from poliomyelitis.

Many types of apparatus have been designed, and are in use, for treating polio sufferers by subjecting the thorax and abdomen of the patient to rhythmic changes in pneumatic pressure, one such type of apparatus being the well known iron lung in which the entire body of the patient, with the exception of the head, is encased. While these different types of apparatus in the main are believed to function effectively for inducing alternate inhalations and exhalations of the patient, they are structurally of such character as to present certain difficulties in use.

A particular object of the present invention is, therefore, to provide, in a manner as hereinafter set forth, a new and novel mechanical lung structure which is so designed as to entirely avoid or materially reduce the difficulties associated with the use of the heavy and difficultly portable mechanical lung structures of known construction.

Another object of the invention is to provide, in a manner as hereinafter set forth, a new mechanical lung structure which is designed with respect to weight, size and manipulation, for easy portability whereby the device, with necessary power supply apparatus and while in operation, is transportable in any standard ambulance or passenger carrying aircraft of five space capacity or more, or in any modern station wagon.

Another object of the invention is to provide, in a manner as hereinafter set forth, a new mechanical lung structure designed so that it may be readily transported manually, with its power supply and while in operation, by a four man team.

Still another object of the invention is to provide a new mechanical lung structure formed to provide an access opening of a length and width equal to the full length and full width of the device, whereby the placing of a patient therewith or removal of a patient therefrom may be accomplished with a minimum of handling and discomfort to the patient and with maximum ease for nurses and attendants.

Another object of the present invention is to provide a new mechanical lung designed in a novel manner whereby it can be made light in weight and can, therefore, be manually transported without requiring any under carriage structure but which, to facilitate such manual handling and transportation is equipped at its ends with extensible handles or carrying bars.

Still another object of the invention is to provide a device of the character stated wherein a new and novel means is provided for effecting an air tight seal between an upper part or section movable to provide the access opening and a lower or base part.

A still further object of the invention is to provide a

2

mechanical lung structure wherein a novel means is provided for securing the main access door whereby the releasing or unlocking of such door and raising the same to open position can be effected in one motion with one hand and from any position along the length of the structure and the same procedure in reverse may be followed for closing and securing the door.

Still another object of the invention is to provide in a structure of the character stated, a novel head supporting means or head rest which is of relatively simple design and at the same time is easily operated for adjusting and supporting a patient's head in the desired position.

The invention has as still another object to provide in a device of the character stated, a new and novel pad or mattress supporting spring unit which is readily placed in or removed from operative position through the main access door.

The foregoing and other objects are attained by the invention, the construction of which will be best understood from a consideration of the following detailed description taken in connection with the accompanying drawings forming a part of the specification, with the understanding, however, that minor changes and modifications may be made in the invention so long as such changes or modifications mark no material departure from the salient features of the invention as expressed in the appended claims.

In the drawings:

Fig. 1 is a view in perspective of a portable mechanical lung structure constructed in accordance with the present invention, the same being viewed from the head end and on the access door side.

Fig. 2 is a perspective view of the device viewed from the foot end and from the side opposite the main access door.

Fig. 3a is a sectional view in a vertical plane extending longitudinally through the center of the head end portion of the lung structure.

Fig. 3b is a corresponding section through the foot end portion of the structure.

Fig. 4 is a transverse section taken substantially on the line 4—4 of Fig. 3b.

Fig. 5 is a detail section on an enlarged scale taken transversely of the hinge connection between the access door and the lower body portion showing details of the sealing means, the section being taken approximately on the line 5—5 of Fig. 1.

Fig. 6 is a sectional view taken substantially on the line 6—6 of Fig. 3b.

Fig. 7 is a sectional detail illustrating the construction of one of the extensible handles, the section being taken substantially on the line 7—7 of Fig. 2.

Fig. 8 is a sectional view on an enlarged scale taken substantially on the line 8—8 of Fig. 1.

Fig. 9 is a view in perspective of the lung with the main access door open, showing the interior design.

Fig. 10 is a sectional view on an enlarged scale taken substantially on line 10—10 of Fig. 1.

Fig. 11 is a detail section showing a portion of the mattress support and a securing hook.

Fig. 12 is a side view of one door brace.

Fig. 13 is a top view of the door brace and adjacent parts of the lung structure.

Fig. 14 is a section on line 14—14 of Fig. 13.

Fig. 15 is a section on line 15—15 of Fig. 13.

Fig. 16 is a section on line 16—16 of Fig. 13.

Referring now more particularly to the drawings it will be seen upon reference especially to Fig. 4 that the portable lung structure of the present invention comprises a body, generally designated 10, which is substantially semi-circular or semi-cylindrical in cross sectional form.

The device is of the all metal monocoque type construction and consists essentially of two basic parts or sections which are designated 10a and 10b. These two sections or basic parts are structurally complete in themselves and are hinged together in the manner hereinafter particularly described.

The portion 10a of the body constitutes the main or base portion while the portion 10b, which is shiftable relative to the base portion constitutes the access door by way of which entrance is had to the interior of the body for placing the patient therein or removing the patient therefrom.

The main or base portion includes the top and back wall forming section 12 of curved form in the transverse direction of the structure which joins in its lower part with a low back wall section 14. This low back wall section merges with the undercurved bottom flange 16 which is continuous along the front and rear sides and across the ends of the base portion and terminates at the inwardly directed edge in the upturned rib 16a. This rib 16a rigidifies the base and the continuous flange 16 provides the supporting bottom for the device.

The portion 10b forming the access door also embodies the top and front wall forming section 18 which is of the same radius as the section 12 with which it is concentric thus forming the substantially semi-circular transverse contour of the body.

The section 18 joins or is continuous with the low front wall section 20.

The ends of the body are closed by the integral head and foot end walls 21 and 22 respectively. These end walls are upwardly and inwardly inclined and each is divided in two parts, the wall 21 being divided in the parts 21a and 21b and the wall 22 being divided in parts 22a and 22b. As shown the parts 21a and 22a are a part of the main or base portion 10a of the body while the end wall parts 21b and 22b are a part of the access door portion 10b.

The main body base portion has the access opening 23 which is defined by the longitudinal top and bottom edges 24 and 25 respectively and the end wall edges 26.

Coinciding with the access opening edges are the corresponding top and bottom longitudinal edges 27 and 28 respectively of the main access door portion and the end wall edges 29 thereof. The meeting edges of these two portions lie in a straight plane at an angle to the bottom of the body structure, which plane cuts across the longitudinal vertical central plane of the body as shown in Fig. 4 whereby the meeting or opposing top edges 24 and 27 lie on the opposite side of the vertical central plane from the meeting bottom edges 25 and 28. Thus there is provided an access opening, when the top section is elevated or raised from the base section, the length and width of which are equal to the length and width of the body proper.

The main access door portion 10b is joined along the top edge 27 thereof with the opposing top edge 24 of the base portion by the hinge 30 which may be of any suitable character but preferably of the type known as a piano hinge and which is illustrated as comprising the two plates 31 and 32 secured respectively to the edges 24 and 27 by rivets 33, or other suitable means, as shown in Fig. 5. These plates carry the conventional interengaging or interdigitating hinge knuckles 34 through which extends the hinge pin 35.

Extending transversely of the base portion of the structure between the inwardly curved bottom flanges 16 are hollow beams 36 which are preferably of U-cross section with the channel directed upwardly and the ends of these beams curve upwardly as indicated at 36a against the inner faces of the flanges 16 as illustrated in Fig. 4.

Overlying each of the beams 36 is a downwardly bowed transversely extending cradle beam 37 which also is preferably of channel form, with the channel directed downwardly as illustrated in Figs. 3a and 3b. The outer ends of the cradle beams are secured to the upturned end por-

tions 36a of the bottom beams 36 as shown in Fig. 4 and the midportion of each cradle beam 37 has the edges of its side flanges in contact with the top edges of the side flanges of the underlying beam 36 as shown in Figs. 3a and 3b.

In addition to the cross beams 36 and 37 there are provided the transverse plates 38 each of which is secured against one side of each pair of cross beams. With this construction a relatively light but strong and rigid bottom frame is provided.

The numeral 39 generally designates the bottom or floor pan which rests upon the concave top surfaces of the cradle beams 37 as shown in Fig. 4 and this pan is bordered along its sides and across its ends by the integral upturned flanges 40 which are welded, riveted or otherwise secured in air tight connection with and against the inner sides of the bottom flanges 16 and the end walls 21 and 22.

At the foot end of the structure the wall 22 has extended therethrough through openings 40' formed adjacent each side of the structure, a guide tube 41 for receiving a sliding handle bar 42. As shown in Fig. 7 the guide tube 41 extends at its inner end through the adjacent cross plate 38 to which it is secured by welding or any other suitable manner. In line with this tube 41 the next adjacent cross plate 38 has an opening 43 formed therethrough, through which slidably extends the inner end of the handle bar 42. Thus the handle bars at the foot end of the device may be shifted inwardly to the position in which they are shown in Fig. 2 or they may be extended for carrying the device. Each bar 42 has secured thereto at its inner end a stop element 44 which limits the outward movement thereof as will be readily obvious.

The head wall 21 likewise has secured thereto and extending therethrough at each side of the device the handle bar guide tube 45 as shown in Fig. 1. The inner ends of these tubes 45 are secured within the structure to cross plates 38 in the same manner as the tube 41 is illustrated in Fig. 7 and accordingly no specific illustration has been made of this construction. Each of the tubes 45 has slidably positioned therein a handle bar 46 which is adapted to be drawn outwardly to a substantial extent when the device is to be manually transported. As shown in Fig. 1 the handle bar guide tubes 45 are of materially greater length than the tubes 41 whereby the bars 46 can be placed in operative position a substantial distance outwardly longitudinally of the device from the head wall 21 to avoid interference with the hereinafter described head rest or support.

The head end wall 21 has formed in the part 21a thereof the head opening 47. Secured to this part 21a in encircling relation with the head opening is a conventional type of collar seal which is generally designated 48. This collar seal is here illustrated as being of the type known as the "spiratwist" wherein there are provided the concentric fixed and rotatable rings 49 and 50 respectively between which are connected the ends of a thin rubber sleeve or cuff which, when the ring 50 is turned relative to the ring 49 is twisted axially to form the iris-like diaphragm 51 having the central aperture 51a.

While a specific type of collar seal has been illustrated it is to be understood that the invention is not limited to the use of a seal of this character as it is contemplated as being within the purview of the invention to use a standard sponge collar seal or a seal of any other suitable form of construction.

Mounted upon the lower part of the head end wall 21 is a head rest which is generally designated 52. This head rest is of relatively simple construction and is readily adjustable to elevate or lower the patient's head to the most comfortable position.

The head rest comprises a pair of brackets 53 which are secured to the part 21a of the wall 21 at opposite sides of the head opening adjacent to the lower portion thereof. Extending forwardly with respect to the head

opening and straddling the same is a substantially U-shaped frame 54 which comprises the side bars 55 and the cross connecting bar 56. The free ends of the side bars 55 are each pivotally attached as at 57 to a bracket whereby the frame may be swung up or down on a transverse axis.

Pivotedly attached at 58 to each bracket above the pivot 57 is one end of a longitudinally slotted brace link 59 the opposite end of which extends downwardly and forwardly across the adjacent frame leg 55 at approximately midway of its ends and extending transversely through each frame leg 55 is a tightening screw 60 which passes through the slot of the adjacent link 59 and carries upon its outer end the thumb nut 61 which when drawn up on the screw draws the head of the screw against the adjacent link to secure the latter in adjusted position.

Suspended between the side arms 55 of the frame 54 is a head rest which comprises a sling 62 formed of a strip of suitable fabric or other material having its ends attached to plates 63. Each of these plates 63, midway between its ends, is attached to or hung on the inner end of a lock screw 60 as illustrated whereby as the frame 54 is raised or lowered the swing will likewise be shifted and due to the single pivotal suspension at each end it will always adjust itself to the most comfortable position for the head of the patient.

Disposed horizontally within the base portion just above the bottom pan 39 is the mattress or pad support which is generally designated 64. This support comprises a sheet 65 of suitable resilient or spring material, preference being had for expanded metal similar to that employed commercially for plaster wall constructions, although the invention is not limited to the use of such.

This expanded metal sheet is, of course, of foraminous form and is of proper length and width to fit the interior of the base portion of the body approximately in the horizontal plane of the bottom edge of the access opening.

The pad support sheet 65 is supported solely by a number of screw hooks 66 surrounding the edges thereof and engaged in apertures along the edges. These hooks have threaded shanks 67 extended through suitable apertures in the base portion wall to the outside and each receives on its outer end, a securing nut 67a. By drawing the hooks outwardly, by the nuts 67a on the outer ends the pad supporting sheet may be drawn to a tight horizontal condition.

As shown in Fig. 9 the pad support lies in the plane of the bottom edge 25 of the access opening or slightly below the same.

In order to maintain an air tight seal between the meeting edges of the access opening and the access door there is provided a continuous sealing coupling generally designated 68. This sealing coupling comprises two coacting parts one of which is carried by the access door on the inner surface thereof while the other part is secured to the inner surface of the wall of the base portion. One of the two parts of the sealing coupling 68 comprises a channel frame which borders the edge of the access door and which is generally designated 69. This channel frame comprises the band strip 70 which, shown in Fig. 5, along the top edge of the access door positions against the hinge plate 31 and is secured by the rivets 33 while other rivets 33a secure the band strip to the door along the end edges and along the bottom edge, one of these other rivets being illustrated in Fig. 6.

The end of the band strip 70 which is adjacent to the access door edge has extending inwardly therefrom the flange 71 and this flange at the inner edge carries the right angularly directed lip 72 which extends in the opposite direction from the strip 70 and thus forms together with the flange 71 and the adjacent or opposing portion of the door wall, a channel 73.

Lying within and extending throughout the length of the channel along the four sides or edges of the access

door is a sealing cushion 74 of rubber or other suitable resilient material.

Coacting with the channel frame and secured to the inner side of the body wall around the access opening is 5 the fixed band strip 75 which along the top edge of the opening lies against the inner side of the hinge plate 32 and secured thereto by the rivets 33 while along the end and bottom edges of the opening suitable additional rivets 33b are provided as shown in Fig. 6 and which 10 rivets along the bottom edge of the opening also pass through the adjacent upturned flange 40 of the floor pan as illustrated.

The band strip 75 carries along the edge thereof which is adjacent to the edge of the access opening, the inwardly extending presser foot 76 for engagement against the resilient pad 74 in the adjacent channel and the face of this foot which engages the pad is transversely curved or convexed as indicated at 77 so as to press firmly into the pad and thus form a tight seal when the coacting 15 parts are brought into operative relation upon the closing of the access door.

The numeral 78 generally designates an access door locking means whereby the door is secured at a number of locations at its lower edge to the adjacent part of the 20 base portion and also whereby the means for securing the door at such several locations may be actuated simultaneously to release the door and swing it upward to open position or to lock the door when it has been closed.

30 The locking means comprises the several articulated units 79 which are secured in the manner about to be described to the bottom edge of the access door, together with the cooperating holding lugs 80 with each of which the unit 79 is coupled.

35 Each of the holding lugs 80 comprises a plate portion 81 which is riveted to the base portion below the bottom edge of the access opening and such plate carries at its upper end the upwardly and outwardly extending portion 82 which terminates in the short downturned lip 40 83 thus forming a downwardly opening or directed angle.

Each of the locking units 79 comprises an upper arm portion 84 which is pivotally attached to the access door at or adjacent to the lower edge as indicated at 85 and the lower arm 86 which is pivotally supported as at 87 between a pair of spaced ears 84a forming a part of the upper arm 84, to swing on an axis parallel to the pivot axis 85 for the upper arm. As illustrated the upper arm 84 is formed on the side adjacent to the access door to receive the lip 83 of a holding lug when the door is closed and the pair of arms are in downwardly hanging position and when in this position an upper end portion 86a of the lower arm 86 is adapted to engage under the tongue 83 in the angle between the tongue and the portion 82 and apply an upward thrust thereagainst when the lower end of the arm 86 is swung inwardly toward the adjacent flange 16 until the pivot axis 87 moves to a past center position with respect to the angle in which the end 86a of the lower arm is engaged.

60 To facilitate the movement of the arms 86 of the several locking units simultaneously the lower or free ends of the arms 86 are connected to the operating bar 88 which extends lengthwise of the device as is clearly shown in Fig. 1. Thus it will be seen that when the bar 88 is pulled outwardly and upwardly the arms 86 of the several latches will be disengaged from the holding lugs and the access door is free to swing upwardly to open position. Obviously, when the door is closed a reverse swinging movement of the bar will re-engage the upper ends of the arms 86 with the lugs to secure the door.

65 For the support of the main access door either fully raised, or opened, or in partly opened position there is provided, at each end of the body, or each end of the 70 access door, a brace, or support unit generally designated 75

89. This unit comprises a bar 90 having a socket forming means 91, at one end in which is engaged the ball head 92 of a stud or post 92a secured to the end wall of the main body portion.

On the adjacent end wall portion of the access door the bar is slidably gripped by the pivoted clamp guide 93, comprising two plates 93a and 93b having in their confronting faces the channels 93c in which the bar is received. These two plates are drawn, or secured, together by a wing screw S which extends through one plate, here shown as plate 93a, and is threaded into the other plate, such as plate 93b, which may be termed the inner or under plate.

The plates are coupled to the ball head 92' of a post 92" secured to the access door, by engagement of the head in confronting sockets 91a and 91b in the opposing faces of the plates, as shown.

As will be seen, loosening of the thumb screw S the bar will be released for sliding movement between the plates to facilitate swinging the access door to open or closed position, or to selected intermediate positions.

While the supporting unit 89 here shown is of a preferred construction, it is to be understood that there is no intention to limit the invention to this construction, as any other suitable brace may be employed.

The numeral 94 designates windows in the top part of the access door top wall section 18 through which nurses or attendants may watch a patient in the lung or give to the patient such attention as may be required. These windows may be formed of suitable fracture-proof glass or transparent plastic and are hermetically sealed around the edges to the edges of the window opening 95 formed through the metal wall or skin of the apparatus body.

To facilitate manual treatment of a patient the wall section 18 of the main access door is provided with a pair of hand holes 96, each located adjacent to one end of the door and these holes are covered by conventional sponge rubber washers or "doughnuts" 97, the opening or hole 98 of which is somewhat smaller than the human wrist which it is intended to encircle when the hand is extended therethrough. These sponge rubber washers 97 are maintained in place by rings 99 placed against the outer sides thereof and riveted as indicated at 100 to the wall of the door and each of the rings has fitted therein the door plate 101 which at its lower edge is hingedly connected to the ring as indicated at 102 whereby it may be swung to open position to uncover the washer 97. When in closed position a pivoted latch element 103 carried by the ring is swung into position over the face of the door plate to maintain it tightly against the underlying washer.

In the central part of the main access door there is provided a rectangular utensil opening 104. Encircling this opening on the outer side of the door is the resilient gasket 105 which is enclosed within and secured in place against the wall 18 by the metal frame 106. This in turn is drawn tightly to position by means of the stud bolts 107 carried by the wall 18 and extending through openings in the frame 106 to receive upon the threaded outer ends thereof the thumb nuts 108.

Adapted to substantially fit the frame 106 is the rectangular door plate 109 which is hinged along its bottom edge as indicated at 110 to the bottom portion of the frame 106 and the frame has pivotally attached thereto at the sides and at the top, the latch elements 110a which are adapted to swing inwardly to secure the door plate 109 firmly against the gasket 105.

The door plate 109 is provided with an arm opening 111, corresponding to the openings 96 and which opening is covered by the sponge rubber gasket 112 positioned against the outer side of the door plate and held in position by the clamping ring 113. This ring like the rings 99 has fitted therein the circular door plate 114 which is

pivoted at the bottom part of the ring and held in place in the same manner as the circular door plates 101.

By the provision of the opening 104 a nurse or attendant is able to place into the mechanical lung body necessary utensils for the use of the patient without having to open the main access door and the provision of the third or centrally located arm opening in the door plate 109 permits a nurse or attendant to work at the head end of the structure by the use of this central opening with the forward opening 96 or at the foot of the structure by the use of the central opening with the rear opening 96.

On the opposite side of the body from the main access door the wall section 12 is provided with the three longitudinally spaced arm openings 115 as shown in Fig. 9.

15 These openings with the sponge rubber gaskets or "doughnuts" and the circular covering doors, designated 116, are of duplicate form and construction as the openings, "doughnuts" and covering doors on the opposite or access door side of the body and accordingly, it is not believed that a detailed illustration of the same is required.

One of the walls of the body, preferably the part 22a of the foot wall 22 is provided with an opening 117 for the connection of a power hose with the interior of the lung structure. A portion of such hose is shown in Fig. 2 25 and designated 118. This hose forms the necessary power connection between the mechanical lung and the portable respirator apparatus such, for example, as the apparatus illustrated in the application of Marvin H. Polzin et al., Serial No. 398,986, now Patent No. 2,780,222.

30 The structure of the present invention is designed for maximum strength and rigidity with a minimum of weight and to this end the metal forming the walls is of relatively light gauge and is suitably strengthened or reinforced, in addition to the channel beams 36 and 37 disposed beneath

35 the floor pan 39, by the circumferentially directed channeled ribs 120 which are secured by rivets or in any other suitable manner, against the inner faces of the top and front wall sections 12 and 18 as shown in Fig. 9. Certain of these circumferentially directed ribs 120 are connected 40 by the short longitudinally directed ribs 121, certain of which border the window openings and the top and bottom edges of the utensil opening, as shown.

In addition to the hose connection port 117 one of the walls, here shown as the wall section 12, is provided with 45 the small port 122 whereby tubes for intravenous feeding or light cords or both may be passed into the body.

As hereinbefore set forth the mechanical lung of the present invention is designed for maximum portability without sacrificing any of those features necessary to the 50 most efficient operation of a device of this character.

As an example, for illustrative purposes only and without intending to limit the invention in any respect to the example, a fully efficient portable lung of the following dimensions has been constructed and used with fully satisfactory results. Inside, the height is approximately 18½ inches; the width is approximately 26½ inches and the length is approximately 71½ inches.

Overall dimensions with carrying gear retracted are: height approximately 22 inches; width approximately 27½ 60 inches, and length approximately 84 inches.

The bare weight of such device is not more than 120 lbs. Accordingly, it will be seen that the device may be conveniently transported in vehicles such as those previously referred to and may easily be manually carried by 65 a four man team while in operation, i. e. with a patient therein, together with necessary accessory equipment.

I claim:

1. A mechanical lung comprising an elongate body 70 designed to completely enclose the torso and limbs of a patient, the body having an overall length, width and height adapting it to installation in a vehicular carrier having interior space limitations corresponding to those of an ambulance, station wagon or the like, the body having a bottom portion and tapering upwardly in a side wall and top forming portion of generally semi-

cylindrical contour, the body being divided longitudinally along a plane which is inclined to the horizontal plane of the base portion providing a main access door and a main body part, means pivotally coupling said door along the top edge thereof to the main body part, said door when opened providing a main access opening extending the full length of the body, a head opening in one end of the main body portion, a neck collar in said opening, and means at the ends of the body upon each side thereof for manually lifting and carrying the same.

2. The invention according to claim 1, wherein the body has end walls which are inclined in upwardly convergent relation, the said plane along which the body is divided passing through said end walls whereby said access door includes a portion of each end wall.

3. The invention according to claim 1, with longitudinally directed tubular guides at the ends of the body adjacent to the sides thereof, and said means comprising handle bars slidably mounted in the tubular guides for longitudinal adjustment from a retracted non-operative position to an extended operative position.

4. A mechanical lung comprising a body designed to enclose the torso and limbs of a patient, the body having a cross section of generally semi-cylindrical outline providing top and side walls, upwardly and inwardly inclined end walls, said side and end walls having inwardly extending bottom portions for a base part, transverse reinforcing members resting upon and secured at their ends to the inwardly extending bottom portions of the side walls, a floor pan resting upon said reinforcing members and secured around its periphery to the side and end walls, said body being longitudinally divided in two parts in a plane lying at an inclination to the horizontal and passing through said end walls providing a main access door part and a main body part, hinge means between the top edge of the door part and the main body part, said access door when raised providing a main access opening of a width and length approximately equal to the length and maximum width of the body, a head opening in one end wall portion of the main body part, a neck collar in said opening, and means facilitating manual lifting and carrying of the body.

5. The invention according to claim 4, wherein said last means comprises telescoping handle bars in the ends of the base portion of the body adjacent to the sides thereof.

6. The invention according to claim 4, wherein said last means comprises tubular guides integral with and extending through the end walls in base portion thereof and handle bars telescopically carried in the tubular guides for sliding movement therein from inoperative to operative position.

7. The invention according to claim 4, with a pad or mattress support comprising a sheet of foraminous material horizontally disposed over said floor pan and means securing the sheet around its edges to the side and end walls.

8. The invention according to claim 4, with means for securing the access door in closed position comprising a plurality of keeper lugs secured to the main body part along the lower edge of the access opening, a plurality of pivoted locking tongues carried by the access door along the lower edge portion thereof and each being designed for locking engagement with a lug when the door is closed, and an actuating bar connected with and common to said tongues for actuating the same as a unit.

9. A mechanical lung comprising a body designed to receive the torso and limbs of a patient, said body having a base flat portion upon which the body rests and top, side and end walls, at least one of said end walls being inclined at an acute angle to the plane of the base portion, the body being longitudinally divided in two parts along a plane passing through the end walls and inclined to the

plane of the base portion forming a minor part access door and a major body part, hinge means connecting the access door along its top edge with the adjacent major body part, a head opening in the inclined wall portion of the major body part, a yieldable neck collar in the head opening, and a head support attached to the outer side of said inclined wall portion adjacent to the lower part of said head opening.

10. The invention according to claim 9, wherein said head support is adjustable and comprises a substantially U-shaped frame having the free end of the side members pivotally attached to the inclined wall in straddling relation with the head opening, angle brace arms each pivotally attached to the inclined wall adjacent to a pivoted

15 end of a side member and extending outwardly at an angle to the adjacent side member, releasable coupling means between each brace arm and the adjacent frame side member, and a head supporting sling suspended in said frame between the side members thereof.

20 11. The invention according to claim 9, with means at each end of the body by which the body may be manually lifted and carried comprising longitudinally extensible handle bars, said means at the inclined wall end of the body including longitudinally extending tubular guides 25 each disposed at the outer side of the U-shaped frame and approximating the length of the frame side members and each having a handle member telescoped thereinto.

12. The invention according to claim 9, wherein said main access door has a minor access opening for the passage of utensils into and out of the lung body, a minor access door hingedly connected to the main access door along an edge of the minor access opening, and sealing gaskets adjacent to and outlining the edges of said main and minor access doors for sealing the doors around the 35 edges of their respective openings.

13. In a mechanical lung including a body designed to enclose the torso and limbs of a patient and formed in two principal parts, one of which parts is a main body part and the other part being a main access door closing 40 a main access opening to the main body part, means forming a seal between the edges of the access door and opposing edges of the access opening comprising a means providing a channel bordering one of said edges and directed toward the opposing edges, a resilient sealing body 45 in said channel, and means bordering the other of said edges and positioned to press into the sealing body to form a tight seal therewith when the access door is placed in closing position over the access opening.

14. In a mechanical lung including a body designed 50 to enclose the torso and limbs of a patient and formed in two principal parts, one of which parts is a main body part and the other part being a main access door closing a main access opening to the main body part, means forming a seal between the edges of the access door and 55 opposing edges of the access opening comprising an inwardly projecting flange bordering the access door on the inner side thereof and having an edge flange forming a channel directed toward the edge of the access opening when the door is closed, a rubber sealing body in said 60 channel, and a presser foot bordering the access opening and projecting inwardly, said foot having a face positioned to enter the channel upon the placing of the access door in closed position and press into and form sealing engagement with the sealing body.
